ATTORNEY

UNITED STATES PATENT OFFICE.

HENRY F. HOLKENBRINK, OF PORTLAND, OREGON.

SERVICE SWITCH BOX.

Application filed May 2, 1921. Serial No. 466,069.

To all whom it may concern:

Be it known that I, HENRY F. HOLKENBRINK, a citizen of the United States, and resident of Portland, in the county of Multnomah and State of Oregon, have invented a new and useful Service Switch Box, of which the following is a specification.

This invention relates more particularly to a means for conducting electrical wires from within a switch box to instruments, or current consuming devices on the outside of said box.

The objects of my invention are to provide a means for bringing wires from within a flush box to instruments, etc. on the outside of said flush box without the employment of any additional pipe or fittings.

I attain these results in the manner described in the following specification and illustrated in the accompanying drawing in which:

Figure 1 is a front elevation of my device. Figure 2 is a side elevation with a portion broken away in section. Figure 3 is a plan with the insulated outlet cover removed. Figure 4 shows a modified form of attaching the insulated outlet cover to the door trim.

Similar numbers of reference refer to the same or similar parts throughout the several views.

Referring in detail to the drawing, I have constructed my device on the usual type of service switch box whose sides 4, top 5 and bottom 6 are provided with the usual knock-out areas 7. A double front 8 at once provides an opening 9 and a stop 10 for the door 11 provided with the usual hinges 12 and a knob 13 for keeping the door properly closed. The front 8 is somewhat larger than the switch box and thereby provides an extending flange about its perimeter.

In the top 5 I have cut an opening 14 over which is placed a partial box consisting of a back 15, sides 16 and top 17 and a lip 18 which passes down through the opening 14 and is preferably spot-welded to the under side of the top 5.

An insulated outlet cover 19 is placed over the open portions thus formed, and wires 20 can readily be passed from meters or other objects desired through the holes 21 in the outlet cover 19 and then down into the switch box to the switches or cutouts as desired. The outlet cover 19 is preferably

of insulating material and is attached to the back 15 by means of the screws 22.

Line 23 represents the face of the wall behind which the switch box sets and against which the door trim 8 rests. 60

Referring to the outlet cover 19 it will be understood that I do not desire to limit myself to a one piece cover of insulating material, but may use a metallic cover through which are passed separate insulating bushings. 65

The principal advantages resulting from the use of this device may be briefly listed as follows: The great convenience of installation caused by the outlet box being part of 70 the switch box and not requiring any pipe or fittings to join the two together; the ease with which wires may be passed from a cutout to a meter, etc. is greatly increased owing to the fact that no additional parts 75 are required in the construction; the cost of production is materially reduced, as well as the cost of installation; the device presents an unusually neat appearance and can be installed in new work as well as old with 80 equal ease. 85

I am aware that switch boxes are in existence from which wires may be carried to the exterior of the box through pipes and fittings to a separate outlet cover, which, 85 owing to their cost of production and installation, I have desired to avoid.

While I have thus illustrated and described my invention it is not my desire to limit myself to this precise form or method 90 of application, but intend that it shall cover all forms and modifications which fall fairly within the appended claim.

What I claim as new is:

The combination of a flush switch box 95 having a front which extends beyond its sides and containing a door and having a rectangular opening cut in its top near said front with an outlet compartment secured over said opening consisting of a vertical 100 back whose lower edge turns under the rear of said opening and is secured thereto and having a top extending from said back to the flush line, side members extending from the compartment top to the flush box top, 105 an insulated cover adapted to close said outlet along the flush line and screws adapted to secure said cover to the back of said compartment.

HENRY F. HOLKENBRINK.
